UNITED STATES PATENT OFFICE.

TONY ORGREN, OF SAN DIEGO, CALIFORNIA.

AERIAL VESSEL.

No. 852,292.

Specification of Letters Patent.

Patented April 30, 1907.

Application filed September 21, 1905. Serial No. 279,499.

To all whom it may concern:

Be it known that I, TONY ORGREN, a citizen of the United States, and a resident of San Diego, in the county of San Diego and State of California, have invented a new and Improved Aerial Vessel, of which the following is a full, clear, and exact description.

The purpose of the invention is to provide an aerial vessel of light, simple and durable construction, in which folding aeroplanes are employed in conjunction with a gas-containing cylinder, and further to provide a gas reservoir having valved connection with the said cylinder, which reservoir when the valve is open automatically maintains a uniform and constant pressure of gas in the cylinder.

Another purpose of the invention is to provide means for holding the aeroplanes in horizontal positions during flight, and also to provide novel and effective propelling mechanisms.

The invention consists in the novel construction and combination of the several parts, as will be hereinafter fully set forth and pointed out in the claims.

Reference is to be had to the accompanying drawings forming a part of this specification, in which similar characters of reference indicate corresponding parts in all the figures.

Figure 1 is a plan view of the vessel and aeroplanes in common horizontal position; Fig. 2 is a side elevation of the vessel; and Fig. 3 is a vertical transverse section drawn upon an enlarged scale, the section being taken through the side paddle wheels.

The body of the vessel consists of a top section A, a corresponding bottom section B and connecting posts 10. The bottom section B is also provided with a triangular bow piece 11, having more or less of an upward inclination. Also in the construction of the body of the vessel the top section A is made to extend out beyond the side edges of the bottom section B.

The aeroplanes C are hinged to the under face of the top section A of the body at a point nearly in vertical alinement with the side edges of the bottom section B, as is shown in Fig. 3. Brace rods 12 are hinged at one end to the outer side edges of the aeroplanes, and when said aeroplanes are in their working or horizontal position they are so held by removably securing the other ends of the brace rods to the bottom section B of the body, as is shown at 13 in Fig. 2.

A cylinder D extends longitudinally of the body at a point just below the top as is shown in Figs. 2 and 3, and the said cylinder D, which is adapted to contain gas, is provided with conical ends 14, that extend beyond the end portions of the body of the vessel. This cylinder D is usually supported by hangers 15 to which it is attached, the hangers being secured to the top section A of the body of the vessel. Below the cylinder D a smaller reserve cylinder D' is located, being parallel with the upper cylinder D, and this lower or reserve cylinder D' is supported by brackets 16, attached to the cylinder and to the bottom section B of the body, as is shown in Fig. 3.

A pipe 17 extends into the lower or reserve cylinder D' and into the upper cylinder D at their central portions, the said pipe terminating short of the upper wall of the upper cylinder and the lower wall of the lower cylinder, and said pipe is provided with a valve 18, located between the cylinders. When this valve 18 is opened the gas in the reserve cylinder can enter the main cylinder D, or any surplus gas in the main cylinder can enter the reserve cylinder D', thus obtaining an automatic circulation of gas in the two cylinders, insuring a uniform and constant pressure of gas in the main cylinder no matter how much said cylinder may contract and expand by reason of meeting with cold or with warm strata of air when the vessel is in flight.

Two paddle wheels E are located at each side of the vessel, being at equal distances from the center, and within each paddle wheel E a propeller wheel E' is adapted to turn, the two wheels E and E' being independently driven. To that end bearings 20 are provided for each group of wheels, secured to the lower cylinder D' by suitable arms 19, as is shown in Fig. 3, and inner bearings 20^a are associated with the bearings 20, the inner bearings 20^a being attached to the upper cylinder D by hangers of any approved type.

Each paddle wheel E is attached to a tubular shaft 21 mounted to turn in the bearings 20 and 20^a, as is also shown in Fig. 3, and each paddle wheel E is of box-like construction, being provided with a broad rim 22, spokes extending from a hub to the rim at its inner edge; and paddles 24 extend out from the rim at a right angle thereto, the said paddles being an equal distance apart.

The paddle wheels E are driven preferably by gasolene motors 25, shown supported from the upper gas-containing cylinder D, and gears 26 on the drive shafts of the said motors are in mesh with gears 27 secured upon the tubular shafts 21 of said paddle wheels.

The shafts 28 on which the propeller wheels E' are mounted, extend through the tubular shafts 21 and are connected with electric motors 29, shown supported upon the lower or reserve cylinder D', as is also shown in Fig. 1. The propeller wheels E' are thus turned independently of their surrounding paddle wheels 15 and the paddle wheels are independent of the propeller wheels. The propeller wheels are of such dimensions that they turn without any hindrance in the said paddle wheels.

A skeleton frame F is located at the stern 20 of the vessel. This frame consists of an upwardly and rearwardly-extending member 30, attached to the central portion of the rear end of the bottom section B of the body, a vertical rear section 31 and an upwardly and 25 forwardly-extending section 32 which is attached to the rear conical end of the gas-containing cylinder D.

A shaft 34 is journaled in suitable bearings 33 located in the vertical member 31 of the 30 said skeleton frame F, and this shaft at its outer end carries a stern propeller F', and the inner end of the shaft is coupled to an electric motor 35, shown suspended from the rear conical end portion of the gas-containing cylinder D.

Braces 36 are shown as resting partially on the upper member of the skeleton frame F, and on the upper face of the rear conical terminal of the gas-containing cylinder D. These 40 braces support an upright 37, and a stem 38 has a ball and socket connection 40 with the said upright 37; and said stem at its rear end carries a rudder blade 39. The rudder blade 39 is operated from within the vessel in any 45 suitable or approved manner. As illustrated ropes or chains 41 and 42 are attached to the inner or handle end of the rudder stem 38, and these ropes or chains are carried in opposite directions over guide pulleys 43 supported at the rear end portion of the upper section A of the body of the vessel, as is 50 shown in Fig. 1.

It will be observed that each driving factor is provided with an independent motor, so 55 that each driving factor is individually under control.

When the vessel is at rest, the aeroplanes C are permitted to drop down to the vertical position shown by dotted lines in Fig. 3, closing the sides of the body.

The gas contained in the main cylinder D will be sufficient to elevate the vessel; the stern propeller F' and the paddle wheels E serve to drive the vessel forward and rearward, and the combined paddle wheels and 65 propellers are utilized to assist the rudder in quickly causing the vessel to turn to the right or to the left, the paddle wheel E of a pair of side wheels being driven for example in one direction and the propeller wheel of 70 the same pair in an opposite direction. The propellers inside of the paddle wheels serve also for the production of wind and as a lifting power, and by their means absolute control of altitudes is obtained.

Having thus described my invention, I 75 claim as new, and desire to secure by Letters Patent,—

1. In aerial vessels, a frame, means for supporting the frame, a propeller for the frame, paddle wheels at the side of the frame, and propellers mounted to revolve within the paddle wheels, said propellers and paddle wheels having independent driving means.

2. In aerial vessels, a body, aeroplanes connected with the upper portion of the body at each side, a gas-containing cylinder located within the body, a propeller at the stern, paddle wheels at the side of the body, and propellers mounted to revolve within the 90 paddle wheels, the propellers and the paddle wheels having independent driving mechanism.

3. In aerial vessels, a body, aeroplanes hinged to the body at its upper side portion, 95 brace rods hinged to the aeroplanes and adapted for removable connection with the body, paddle wheels mounted to revolve in the said body, two at each side an equal distance from the center, a propeller mounted to revolve within each paddle wheel, an independent motor for driving each paddle wheel and each propeller, a stern propeller, and an independent motor for the same.

In testimony whereof I have signed my name to this specification in the presence of two subscribing witnesses:

TONY ORGREN.
